UNITED STATES PATENT OFFICE.

CHARLES F. DOBLE, OF QUINCY, MASSACHUSETTS, ASSIGNOR TO WILLIAM H. DOBLE,
OF QUINCY, MASSACHUSETTS.

DISHWASHING MACHINE.

Application filed March 10, 1924. Serial No. 638,024.

To all whom it may concern:

Be it known that I, CHARLES F. DOBLE, a citizen of the United States, residing at Quincy, county of Norfolk, State of Massachusetts, have invented a certain new and useful Improvement in Dishwashing Machines, of which the following is a specification, reference being had therein to the accompanying drawings.

10 The invention relates to a new and useful improvement in dish washing machines. It relates especially to a dish washing machine in which the dishes are supported in a holder above the level of the water in a

15 tank and the water is dashed against the dishes. The object of the present invention is to provide means for varying at will the necessary amount of hot water required for a predetermined level of water in the tank.

20 The invention consists in providing a displacement member or members which can be adjusted as desired to lessen the amount of water required for maintaining the water at a predetermined level in the tank.

25 The invention will be fully understood from the following description when taken in connection with the accompanying drawings, and the novel features thereof will be pointed out and clearly defined in the 30 claims at the close of this specification.

In the drawings:

Fig. 1 is a vertical section of a dish washing machine embodying the invention, the displacement members being shown as set 35 to their position of greatest displacement.

Fig. 2 is a horizontal section.

Fig. 3 is a fragmentary, vertical section showing in dotted lines the displacement members turned up into a substantially non-displacement position.

Referring now to the drawings:

There is shown at 1 a cylindrical tank mounted on a base 2 having supports 3. There are shown supported within the tank 45 suitable dish holders of skeleton or reticulated formation, the said dish holders which are shown consisting of the members 4, 5 and 6 for holding different kinds of articles to be washed. A vertical driving shaft 7 extends through the bottom of the tank, the lower end of said shaft being detachably connected with a motor shaft 8 driven by a motor 9. The said shaft 7 is journalled in a bearing 10 in the bottom of the tank which 50 carries at its upper end a bevel gear 11

which meshes with a bevel gear 12 mounted on a horizontal shaft 13 whereby the said shaft 13 is rotated. A rotor casting 14 is revolvably mounted upon the bearing 10 as an axis. Said rotor has upright bearing members 15, 15', within which the shaft 13 is journalled, said bearing members 15, 15', being connected by tie-rods 16. A pump casing 17 of a centrifugal pump projects from said rotor casting on the opposite side of its axis of rotation from the shaft bearing members 15, 15'. The shaft 13 extends through the bearing member 15 and is journalled also in the pump casing 17.

Mounted fast on the shaft 13 are propeller blades 18 which revolve with the shaft 13 and throw the water upwardly over the dishes in the rack. Preferably a semi-cylindrical screen 19 is provided which partially surrounds the propeller blades.

Fast on the shaft 13 within the pump casing 17 is a bladed rotary piston 21 which rotates with the shaft. The pump piston and the propeller blades rotate simultaneously on a horizontal axis and revolve 70 together about a vertical axis. Water is admitted into the pump casing through a pipe 22 and is driven upwardly by said piston 21 through the outlet 23 into a pipe 24 which passes up through the dish racks 4, 5 and 6. The said pipe 24 is provided at its upper end with a discharge nozzle 25 which discharges the water over the dishes in the racks as the rotor casting revolves, carrying with it the pump and the propeller. The tank 90 is provided with a draw-off opening 26 provided with a suitable fitting 27. The water may be introduced into the tank in any convenient way. It may be done by removing the nozzle 25 temporarily and connecting the upper end of the pipe 24 with a filling hose, or filling it in any other way desired.

When in operation the water level is preferably maintained at or slightly above the shaft 13 of the rotor. In the drawings, 100 the water level is shown at 280.

Adjustable displacement members for the purpose previously specified are provided. Preferably there are two displacement members on opposite sides of the rotor, as shown 105 in the drawings for more complete regulation and control of the water, although the device is operative with only one displacement member. The displacement members may be of any form and operated in any 110

way desired. For the purpose of illustration I have shown the preferred form and method of operating the same as follows. The two displacement members 28, 28 are alike and are operated simultaneously. Each displacement member 28, as shown in the drawings, is in a general way segmental in contour having an outer curved periphery 29 co-axial with the circular contour of the 10 tank but of smaller radius and on its inner edge 30 it follows the irregular contour of the rotor to which it is attached including the casting 14, the pump casing 17, the pipe 22, and the propeller casing. Each displacement member is hinged at 31 to the 15 rotor, the hinges being shown at 32. The displacement members are shown in Fig. 3 in full lines in their downward position for full displacement and are shown in dotted 20 lines in their elevated position. There is an annular space 43 between the outer periphery of the displacement members and the wall of the tank. The thickness of the displacement members is preferably about 25 equal to the normal predetermined depth of water, the water being in the annular space 43 and other vacant spaces not occupied by the displacement members and the rotor mechanism. By turning the displacement 30 members up more or less on their hinges, the available water space is varied. In order to provide means for operating the displacement members there is provided a vertical rod 33 whose lower end has a flexible connection 35 with each one of the displacement members at some point intermediate the hinge and the outer periphery of the displacement member, the said connection shown consisting of links 34, 35, one end of 40 each of which is connected flexibly with the displacement member by means of eyes 36, 37, respectively, and the other ends of said links 34, 35, are connected with a ring 38 on the lower end of said rod 33. 45 The said rod 33 extends upward into a position in the upper part of the tank where it can be readily reached by the operator and is preferably provided with a handle 40. Preferably the said rod extends up along 50 side of the water pipe 24, passing through guides 41, 42. Preferably a spring latch 44 is provided for holding the rod 33 in its adjusted position. Any other suitable holding means may be used. 55 The displacement members will move around with the rotation of the rotor on a vertical axis and the propeller blades will also rotate on a horizontal axis. 60 The displacement members may be of wood, metal or any other material. They may be solid or hollow and of any suitable shape. The inner contour will preferably be determined by the shape of the rotor and its attached mechanism. 65 It is obvious that by the use of my dis-

placement mechanism a predetermined water level may be maintained with much less quantity of water than without such a device.

What I claim is:

1. In a dish washing machine, the combination with a receptacle to hold the washing fluid, means to support dishes within the receptacle above the normal level of the fluid, means in the lower part of the receptacle 70 to project the fluid against the dishes while supported on the holder, and an adjustable fluid displacement member which is adapted to partially fill the water space in the receptacle.

2. In a dish washing machine, the combination with a receptacle to hold the washing fluid, means for supporting the dishes within the receptacle above the level of the fluid, a rotary member in the lower part of 75 the receptacle to project the washing fluid against the dishes, and an adjustable fluid displacement member which is adapted to partially fill the water space in the receptacle between the said rotary member and the wall of the receptacle, said displacement member being connected with the rotary member and rotating therewith.

3. In a dish washing machine, the combination with a receptacle to hold the washing fluid, means for supporting the dishes within the receptacle above the level of the fluid, a rotary member in the lower part of the receptacle to project the washing fluid 80 against the dishes, an adjustable fluid displacement member which is adapted to partially fill the water space in the receptacle between the said rotary member and the wall of the receptacle, said displacement member being connected with the rotary member, 85 and means for turning said displacement member up on its hinge to lessen the area of displacement below the normal water level.

4. In a dish washing machine, the combination with a receptacle to hold the washing fluid, means for supporting the dishes within the receptacle above the level of the fluid, a rotary member in the lower part of the receptacle to project the washing fluid 90 against the dishes, an adjustable fluid displacement member which is adapted to partially fill the water space in the receptacle between the said rotary member and the wall of the receptacle, said displacement member being connected with the rotary member and rotating therewith, said displacement member being hinged to the said rotary member and an upwardly extending rod 95 connected at its lower end with said displacement member, the upper end of said rod being accessible for operation in the upper part of the receptacle to adjust the position of the displacement member.

5. In a dish washing machine, the combi- 100

nation with a receptacle to hold the washing fluid, means for supporting the dishes within the receptacle above the level of the fluid, a rotary member in the lower part of the receptacle to project the washing fluid against the dishes, an adjustable fluid displacement member which is adapted to partially fill the water space in the receptacle between the said rotary member and the 10 wall of the receptacle, said displacement member being connected with the rotary member and rotating therewith, an upwardly extending pipe carried by the rotary

member through which the washing fluid is forced having a discharge outlet through 15 which the fluid is discharged upon the dishes, said displacement member being hinged to said rotary member, and an upwardly extending rod alongside of said pipe connected at its lower end to said displacement member and having an operating handle at its upper end, and guide members through which the said operating rod passes.

In testimony whereof I affix my signature.
CHARLES F. DOBLE.
